Wisconsin

UNITED STATES PATENT OFFICE.

ALFRED E. WITTIG, OF ROCHESTER, NEW YORK.

SIGNAL.

1,257,661.

Specification of Letters Patent. Patented Feb. 26, 1918.

Application filed January 7, 1916. Serial No. 70,770.

To all whom it may concern:

Be it known that I, ALFRED E. WITTIG, a subject of the Emperor of Germany, and resident of Rochester, in the county of Monroe and State of New York, have invented certain new and useful Improvements in Signals, of which the following is a specification.

This invention relates to signals. It is intended for attachment to a motor-vehicle so that it can be operated by the driver, and its object is to indicate to others the direction in which the vehicle is about to turn.

Signals for this purpose have been tried and used to some extent, but have been more or less cumbersome and complicated, occupying space on the vehicle required for other purposes. The invention in question is compact in form, inconspicuous when not in use, cheap to manufacture, and may readily be attached to or detached from a vehicle.

In the drawings.—

Figure 1 is a rear elevation, partially in section, of a signal embodying this invention; and

Fig. 2 is a bottom view thereof.

The signal proper consists of a set of lazy-tongs 5 adapted to be folded within a casing 6, supported on one end of a bracket 7 that in turn is adapted to be clamped to the side-tube 8 of a wind-shield, such as is ordinarily used on motor-vehicles, so that it may readily be detached therefrom. The side of the casing 6 that is nearest the clamp 7 is tubular in cross-section, as indicated by the numeral 9, and within this tubular portion a cylindrical block 10 is adapted to move in a vertical path. One member of the lazy-tongs 5 is pivoted to the block 10 and its other member is pivoted to the casing 6 at 12.

When the device is not in use the lazy-tongs 5 lie within the casing 6, as indicated by the dotted lines in Fig. 1, and when the indicator is in use the lazy-tongs are extended as shown in full lines in Fig. 1, so as to be visible to the driver of a vehicle approaching from behind. The extension of the lazy-tongs 5 is accomplished by the depression of a plunger 13 that is slidably mounted on a post 14 which is part of a clamp-bracket 15. This bracket is attached to the steering-column 16 of the vehicle, or in some other position conveniently within reach of the driver. One end of a stiff wire 17 is fixed

within the head of the plunger 13, and this wire extends through a flexible casing 18 and its other end is attached to the block 10. The depression of the plunger 13 moves the wire 17 and the block 10 upwardly, causing the lazy-tongs 5 to be fully extended, and the elevation of the plunger 13 moves the block 10 downwardly, causing the lazy-tongs 5 to be retracted within the casing 6. In its retracted position the device is inconspicuous, and because of its attachment to the wind-shield it occupies a space on the vehicle which is seldom required for other purposes.

To render the signal or indicator visible at night a light is employed. Preferably this is an incandescent bulb 19 supported within a hood 20 on a portion of the clamp-bracket 7, which may be in line with apertures 21 in the casing 6. One or both of these apertures may be filled with a sheet of colored glass.

When the plunger 13 moves downwardly it comes into contact with two brushes 22 and 23 supported on an insulating block 24 on the bracket 15 and completes the circuit through the lamp 19. Wires 25 and 26 are shown connecting the lamp with a battery 27. The lamp is located at the rear of the casing 6, so that its light will be visible to one approaching from the front. This position of the lamp throws the rays of light from the lamp upon the rear side of the lazy-tongs 5 so as to make the latter visible to anyone coming up behind. The part 5 may be painted a bright color adapted to reflect the light-rays, this bright color also serving to attract attention in daylight.

One of these devices may be attached to each side of the wind-shield, so that the driver of the vehicle can readily indicate in which direction he intends to turn. Obviously, the particular construction of the indicator may be varied to suit conditions of use, and is not limited to the exact construction and proportions shown in the drawings.

I claim:—

1. The combination of an extensible signaling arm, a casing adapted to contain the same in its retracted position and having apertures in opposite walls, means for extending and retracting said arm, a bracket adapted to support the casing upon the vehicle, and an electric light attached to the bracket to one side of the casing and having

a reflector arranged to throw light both outwardly on the signaling arm when extended, and through the apertures in the casing.

2. The combination of an extensible signaling arm, a casing adapted to contain the same in its retracted position and having apertures in opposite walls filled with colored glass, means for extending and retract-

ing said arm, a bracket adapted to support the casing upon the vehicle, and an electric light attached to the bracket to one side of the casing and having a reflector arranged to throw light both outwardly on the signaling arm when extended, and through the glass in the apertures in the casing.

ALFRED E. WITTIG.
